UNITED STATES PATENT OFFICE.

ORVILLE E. HOUSER, OF CHILLICOTHE, OHIO.

AIR-COMPRESSOR.

1,321,920.

Specification of Letters Patent. Patented Nov. 18, 1919.

Application filed July 20, 1916. Serial No. 110,262.

To all whom it may concern:

Be it known that I, ORVILLE E. HOUSER, a citizen of the United States, residing at Chillicothe, in the county of Ross and State 5 of Ohio, have invented certain new and useful Improvements in Air-Compressors, of which the following is a specification.

This invention relates to air compressors and is particularly directed to a compressor 10 unit which may be installed in garages or, in fact, any place where a uniform air supply is desired. The main object of my invention resides in a comparatively simple type of structure whereby a uniform pressure 15 sure may always be maintained, the compressor itself being rendered inoperative when the predetermined pressure has been reached.

A further object of my invention resides 20 in novel means of supporting and also of driving the compressor. This novel supporting means take the form of hangers directly supported from the drive shaft, thus leaving the air cylinder and its component parts suspended thereon. Further, 25 the driving mechanism is directly connected to the supporting shaft whereby the compressor may be supported any place desired and may also be adjustable in its support 30 between bearings for the line shaft.

Still a further object of this invention resides in the novel combination of elements 35 serving as an automatic cut off for the air supply when the tank pressure has reached a predetermined amount. As a primary element for accomplishing this automatic cut off, I use a Bourdon tube so connected and arranged that the supply of air to the tank is automatically cut off when the desired 40 pressure is reached.

The preferred embodiment of my invention is shown in the accompanying sheets of drawings, in which similar characters of reference designate corresponding parts, 45 and in which:

Figure 1 is a view in front elevation of my air compressor shown suspended from its driving shaft,

Fig. 2 is a view in side elevation of the 50 upper or driving portion of the compressor structure,

Fig. 3 is a view in central vertical section through the lower portion of the air cylinder,

55 Fig. 4 is a horizontal section taken on line 4-4 of Fig. 3, and,

Fig. 5 is a sectional view taken on line 5-5 of Fig. 4 and showing the adjustment means for determining the pressure at which the compressor structure is rendered 60 inoperative.

In these several views, the air compressor proper is shown as comprising a cylinder 1 of the ordinary type within which a piston 2, connected to a connecting rod 3, operates. 65 This cylinder is preferably held in inverted position as is shown and its upper inverted end is provided with a pair of outstanding pierced lugs 4 within which the hanger rods 5 are supported. The upper ends of these 70 hanger rods carry bearings 6 which may be of any preferred type and which form the means for supporting the compressor as a whole, from the line or drive shaft 7. It will be understood that this line shaft is 75 rotatably journaled in the bearings 6 and in order to add stability to some degree to prevent the cylinder from rocking during its normal operation, tie rods or brace rods 8 may be provided and may be attached to 80 any convenient point. The upper end of the connecting rod 3 is provided with an eccentric structure 9 of such size that a complete rotation of the line shaft 7 causes the piston to move from one end of the cylinder to the other. From this arrangement, 85 it will be apparent that such wear as may occur to the bearings 6 during their continued use, will in no way affect the successful operation of the compressor, since any wear 90 which takes place would occur on the upper half of the bearings 6 and this would simply very slightly increase the clearance between the end of the piston 2 and the cylinder head. Thus it will appear, that the 95 compressor may be supported at any desired position upon the line shaft 7 and further, 100 that the compressor is adjustable as to its position along its line shaft between its supporting bearings. This is a decided advantage in a great many places, since it is often desirable to shift the compressor to make room for machines of other types.

Referring to Fig. 3, the cylinder head is 105 designated by the reference numeral 10 and this head is provided with a pair of valve seats to receive the intake valve 11 and the exhaust valve 12. Both of these valves 11 and 12 are suitably supported within fittings 13 screwed into the head 10, as is 110 shown and both valves are urged toward their seat by means of separate springs

designated by the reference numeral 14. The lower end of the valve stem 15 of the exhaust valve is slidably fitted in the cap 16, while the stem 17 of the intake valve projects through this cap 18 and carries the cup element 19 at its lower end in which its spring 14 rests, this cup element being locked in position by means of the lock nut shown at 20. Depending from the head 10 are a pair of bolts 21, which bolts rigidly carry the table strip 22 at their lower ends. Pivotally secured, at 23 to this table strip 22 is a bell crank 24, whose long arm 25 projects out a distance to be movable beneath the lock nut or wearing nut 20 on the lower end of the stem 17 of the intake valve. The arrangement is such that when the pressure has reached a predetermined amount, the arm 25 of this bell crank is moved to a position beneath the valve stem 17 to hold the valve 11 in slightly elevated position so that any air taken into the cylinder will also be exhausted through this same valve when the piston 2 descends. The means for so moving this bell crank is the Bourdon tube shown at 26. The rear end of this tube is connected at 27 to a short by pass section 28 of the conduit 29 leading to the storage reservoir, this pipe 29 being also in communication with the exhaust passage through the pipe 30. This storage tank has not been shown, but it is believed that this principle is understood well enough so as not to be necessary to add this to the drawings, it being sufficient to state that the conduit 29 leads to this storage tank and that the Bourdon tube 26 is in communication with the air in this tank through the by pass 28. The opposite end 40 of this Bourdon tube is pivotally connected at 29^a to a link 29 which connects this spring with the short arm 30 of the bell crank. The means of pivotally connecting this link 29 with the arm 30 is shown in detail in 45 Figs. 4 and 5 and comprises a stud 31 having a threaded shank 32 on its underside, which stud is rigidly secured to the arm 30 by means of this shank and the nut 33. The top surface of the stud is drilled and tapped 50 slightly off its center to receive the screw 34, which screw in reality forms the means of pivotal connection between the link 29 and the bell crank arm 30.

Thus, when the pressure within the storage tank increases due to the continued operation of the compressor structure, the Bourdon tube will tend to straighten out and its free end thus causes the bell crank 24 to move about its pivotal center 23 to 55 gradually bring the arm 25 to a position beneath the valve stem 17. On each suction stroke of the piston, it will be understood that this valve is elevated from its seat and consequently the stem is also elevated and 60 it is during one of these elevated periods

that the arm 25 is permitted to slide into a position beneath the stem. When this occurs, the valve 11 is held from its seat so that the air drawn into the cylinder will also be exhausted through the opening thus 70 created and will not enter the storage tank through the valve 12. Should it be desired to vary the pressure at which the structure is rendered inoperative, the stud 31 is adjusted about its center shank 32 which correspondingly moves the point of pivotal connection 34 between the link 29 and the upper side of the stud 31. This causes a shifting of the short arm 30 which correspondingly shifts the long arm 25 either toward or away from the valve stem, depending upon the direction in which the stud 31 is rotated.

From the foregoing description, taken in connection with the accompanying sheets of drawings, it will be apparent that I have provided a comparatively simple type of air compressor and one which may be readily held supported or suspended from the line shaft, as may be desired. Further, it will be apparent that comparatively simple means for regulating the pressure at which this compressor structure is rendered inoperative, are also provided. This pressure may be regulated by simply turning the 85 stud 31 about its central shank 32 which correspondingly shifts the pivotal center 34, thus moving the bell crank about its center to cause the long arm 25 to change its relative position with respect to the under surface of the intake valve stem 17. On the suction stroke of the piston, this valve stem is elevated, which permits its long arm 25 to assume a position beneath the valve stem to 90 hold it open to thereby permit the exhaust of the air through the intake valve after it has been drawn into the same.

What I claim, is:

1. In an air compressor, in combination, a piston, a cylinder, a compressed air pipe leading from said cylinder, an intake valve and stem in said cylinder, a Bourdon tube in communication with said pipe, a pivotally supported bell crank, a link connection between one arm of said bell crank and the free end of said tube to move the other arm under said valve stem when the pressure has reached a predetermined amount, and means for adjusting said link connection to vary the pressure at which said valve 110 is held open.

2. In an air compressor, in combination, a cylinder suspended from a driving shaft and disposed head downward, pressure responsive inlet and exhaust valve structures 115 situated in the head of said cylinder, a discharge pipe structure extending from said exhaust valve structure, a Bourdon tube in communication with said pipe structure, a shiftable lever supported by said cylinder 120

125 130

and arranged to engage when in an active position with said inlet structure to prevent actuation of the latter, means connected with the free end of said tube and said lever 5 to throw the latter to an active position when the pressure in said pipe structure reaches a predetermined poundage, and adjustable means coöperative with said lever

to vary the pressure at which the latter will be operated.

In testimony whereof I affix my signature in presence of two witnesses.

ORVILLE E. HOUSER.
